(57) **CLAIM**

The ornamental design for a cap for packaging container, as shown and described.

DESCRIPTION

FIG. 1 is a perspective view of a cap for packaging container, showing my new design.

FIG. 2 is a front view thereof.

FIG. 3 is a rear view thereof.

FIG. 4 is a top plan view thereof.

FIG. 5 is a bottom plan view thereof.

FIG. 6 is a right side view thereof; and,

FIG. 7 is a sectional view taken along line 7-7 of FIG. 2 thereof.

In the drawings, the evenly spaced broken lines are shown for the purpose of illustrating parts of the article that form no part of the claim. The dot-dash lines represent the boundaries of the claim and form no part thereof.

1 Claim, 7 Drawing Sheets
